UNITED STATES PATENT OFFICE

FRIEDA MOLDENHAUER, OF WATERTOWN, WISCONSIN

CURTAIN STRETCHER

Application filed February 25, 1930. Serial No. 431,113.

This invention relates to improvements in curtain stretchers.

In stretching and drying lace curtains, it has been found to be very difficult to properly support curtains of this type, particularly those made of Irish point lace and similar fine material, where the curtain is supported from the top by a rod or the like run through the usual top hem, and providing a weighted member at the bottom of the curtain, it being necessary in nearly all cases to form a temporary hem at the bottom of the curtain through which a weighted rod is passed for holding the curtain in proper stretched position during the drying.

It is, therefore, one of the objects of my invention to provide means whereby fine lace curtains, such as those constructed of Irish point lace, or the like, and those provided with scalloped ends can be quickly and easily dried through the medium of a weighted rod applied to the lower end of the curtain by means of movable members carried by the rod and adapted for engagement with the lower end of the curtain.

Another object of my invention is the provision of a curtain stretcher which includes a supporting rod adapted to be run through the usual top hem of a curtain and a weight rod having loosely mounted thereon, a plurality of hook members which are adapted to engage the lower end of the curtain for supporting the weight rod in position at the lower end of the curtain and applying the proper amount of stretching medium to the bottom of the curtain during the drying of the curtain, so that after the same has become thoroughly dried, it will be stretched out to a smooth even surface and the longitudinal edges will be stretched equally with the body of the curtain.

A further object of my invention is the provision of a curtain stretcher of the above type which is of an extremely simple nature so that it can be manufactured and placed on the market at a very low cost, but at the same time embodies sufficient means for carrying out the purpose for which it is intended.

With the above and other objects in view, the invention consists in the novel features

of construction, the combination and arrangement of parts hereinafter more fully set forth, pointed out in the claim and shown in the accompanying drawing wherein:

Figure 1 is a front elevation illustrating the application of my improved curtain stretcher;

Figure 2 is a detail sectional view on the line 2—2 of Figure 1 taken through the rod and the lower portion of the curtain, showing how the weight rod is connected to the lower end of the curtain.

As illustrated in the drawing, Figure 1 discloses the use of my improved curtain stretcher and in this construction, I provide a supporting rod 1 which may be suspended from any support by means of the eye screws 2, the loops 3 of which receive the ends of the rod 1, as illustrated. In applying the rod 1 to the curtain, it is passed through the usual looped end 4 of the curtain, which is ordinarily used for supporting the curtain upon an ordinary curtain pole. After the rod has been passed through the loop 4, the ends of the rod are engaged with the loop or eyes 3 of the screw members 2.

As stated heretofore, it has been necessary, when stretching curtains, that are not provided with a hem or loop at the bottom to provide a temporary loop for receiving the weight rod and this type of construction is objectionable in view of the fact that after the weight rod has been removed, the lowered end of the curtain is creased or wrinkled where a temporary hem has been placed in the curtain and it is necessary to press or iron out the lower end of the curtain.

In order to overcome the objectionable feature of necessarily forming a loop or hem in a fine Irish point lace curtain or similar types of material, I provide the usual weight rod 5 and slidably mounted upon this rod 5 are a plurality of loops 6. These loops 6 are formed of short lengths of heavy wire, each length having one end folded upon itself to provide the loop 6, with the other end extending beyond the loop at an obtuse angle, as shown at 7 and at the extremity of the second end, I provide a small hook 8 which is formed by bending over the extremity of the

second end of the wire, and extending this bent end toward the opposite side of the obtuse portion from the first end as clearly illustrated in Fig. 2. From the above, it will be apparent that these loops 6 can be loosely mounted upon the rod 5 and the hook members 8 engaged with the lower end of the curtain 9 at spaced intervals.

In Figure 1 of the drawing, I have illustrated my improved curtain stretcher as applied to a comparatively fine lace curtain having a lower scalloped end and it will be noted that in order to properly support the rod 5 at the lower end of the curtain, one of the loops 6, together with its hook 8 is positioned upon the rod 5 directly beneath one of the scallops 10, the hook 8 of each loop being engaged with each scallop at approximately its central portion or what might be termed the high point of the scallop, thus by providing the proper number of loops for an equal number of scallops and engaging a hook 8 with each scallop, the weight of the rod 5 will be equally distributed at the lower end of the curtain, and due to the particular shape and relative position of the hook 8 with respect to the loop 6, the rod 5 will be supported directly beneath and in a line with the curtain, as shown in Figure 2, so that during the drying of the curtain, the weight of the rod 5 will have a tendency to produce a stretching action upon the curtain which will be equally distributed throughout the entire area of the curtain.

In applying my improved stretcher to comparatively fine lace curtains where the scalloped lower end is eliminated, it is essential that the loops 6 and hook 8 be equally distributed across the lower end of the curtain so that the weight of the rod applied to the body of the curtain will be equally distributed over the curtain and these loops 6 can be equally adjusted upon the rod due to the fact that these loops are loosely mounted and can be moved to any position desired.

It will also be apparent that as soon as the curtain has become thoroughly dried, the small hook members 8 can be disengaged from the material of the curtain and the material will not be effected in anyway whatever, due to the fact that the pulling weight of the rod is equally distributed among the several hooks applied to the bottom of the curtain.

From the above, it will be apparent that I have provided a very simple and inexpensive curtain stretcher which will prove extremely useful for stretching high grade lace curtains, without the necessity of providing a temporary hem or loop at the lower end of the curtain for the application of a weighted rod or the like, and the curtain can be quickly and easily mounted upon my improved stretcher or removed therefrom.

Attention is also directed to the fact that

due to the extreme simplicity of my invention, it can be manufactured and placed on the market at a very low cost.

While I have shown and described the preferred embodiment of my invention, it will be apparent that slight changes may be made in the construction when putting the invention into practice without departing from the spirit of the same or the scope of the appended claim.

I claim:

In a curtain stretcher and drier, a curtain having a loop at its upper end and ornamental, spaced points at its lower end, a supporting rod adapted to be in removable position in the upper curtain loop for evenly supporting the curtain throughout its entire width, in combination with a gravity stretcher comprising a rod of predetermined weight and a plurality of hooks slidable thereon adapted to engage the curtain points for imparting a plurality of even applications of the weight rod to the curtain throughout its width whereby the upper portion of the curtain is smoothly stretched and the lower portion thereof is stretched at spaced intervals to develop a series of gentle folds or flutes at said lower end of the curtain resulting from unduly stretching the fabric of said curtain at spaced intervals.

In testimony that I claim the foregoing I have hereunto set my hand at Watertown, in the county of Jefferson and State of Wisconsin.
